UNITED STATES PATENT OFFICE.

JOHN J. KARTHEISER, OF CHICAGO, ILLINOIS, ASSIGNOR, BY DIRECT AND MESNE ASSIGNMENTS, TO KARBUAB COMPANY, OF CHICAGO, ILLINOIS, A CORPORATION OF ILLINOIS.

CARBURETER.

1,297,572.

Specification of Letters Patent. Patented Mar. 18, 1919

Application filed September 14, 1914. Serial No. 861,528.

To all whom it may concern:

Be it known that I, JOHN J. KARTHEISER, a citizen of the United States, and a resident of Chicago, in the county of Cook and State 5 of Illinois, have invented a certain new and useful Improvement in Carbureters, of which the following is a specification.

This invention relates to carbureters.

Primary objects of the invention are to 10 provide means in a carbureter for properly proportioning the quantities of air and of hydrocarbon supplied to the carbureter to produce practically a uniform explosive mixture of high efficiency under all conditions 15 of hydrocarbon feed for which the carbureter is designed and adapted; a further object of the invention is to provide effective means for thoroughly breaking up the hydrocarbon and for thoroughly mixing said 20 hydrocarbon vapor and air.

To effect the foregoing objects, a carbureter of my invention comprises the various features, combinations of features and details of construction hereinafter described 25 and claimed.

In the accompanying drawings in which my invention is fully illustrated,

Figure 1 is a central, vertical, sectional view of my improved carbureter.

Fig. 2 is a sectional plan view thereof on the line 2—2 of Fig. 1.

Fig. 3 is a partial vertical sectional view, slightly enlarged, taken on the line 3—3 of Fig. 1.

Fig. 4 is a sectional view on the line 4—4 of Fig. 1.

Fig. 5 is a partial view similar to Fig. 1 showing the valves open; and

Fig. 6 is sectional plan view on the line 40 6—6 of Fig. 1.

My improved carbureter comprises a body portion, designated as a whole A, formed in which is a mixing chamber A'. To provide access to said chamber, one side or end thereof 45 is closed by a removable plate a and, if considered desirable, both ends thereof may be thus removable.

The carbureter is adapted to be connected to the manifold in the usual manner, and is 50 provided with a discharge opening 1 which connects the mixing chamber A' directly with the manifold.

Instead of employing a single jet or nozzle for supplying hydrocarbon to the carbureter,

I employ a plurality of separate nozzles and 55 corresponding air admission openings so arranged and controlled that they may be brought successively into communication with the chamber A'. As shown, there are five separate nozzles designated, respectively, 60 2, 3, 4, 5 and 6 located in separate air admission passageways 2', 3', 4', 5' and 6'. Hydrocarbon is supplied to the nozzles from a float reservoir A² through passageways 7 formed in the body portion of the carbureter. Where the passageways 7 extend 65 across the air supply passages, the body portion of the carbureter is cored out to provide the necessary passageways, as shown at 8, Fig. 3. 70

As compared with hydrocarbon supply nozzles heretofore used, the nozzles of my improved carbureter are characterized by the feature that the jet orifices thereof are relatively much smaller; which in combination 75 with the separate air admission passageways therefor and the means for bringing the same separately and successively into communication with the mixing chamber A', obviously renders it possible to produce a practically 80 uniform and properly proportioned explosive mixture, thus insuring maximum efficiency and economy of hydrocarbon.

My invention contemplates the use of any desired or approved form of float reservoir 85 A², which need not therefore be described in detail.

In order to provide for varying the proportions of air and of hydrocarbon so as to produce an explosive mixture which shall be 90 richer or poorer in hydrocarbon as may be desired, means are provided for varying the effective suction exerted on the nozzles by the motor when said nozzles are in communication with the mixing chamber, which will 95 operate to draw relatively more or less hydrocarbon from said nozzles as said suction is increased or decreased. As shown, said means consists of a butterfly valve 9 located in a downward hollow extension 10 of the air 100 admission passageway 2', which, in the case of an automobile, is adapted to be controlled by the driver of the car by means of a usual lever on the steering post, not shown, which is operatively connected with the stem of 105 said valve, said connection, as shown, comprising a usual crank arm 11 on said valve stem and a connecting rod 11'. With this

construction it is obvious that, if only the air passageway 2' is in communication with the mixing chamber A', partly closing the valve 9 will reduce the size of said air admission passageway and will increase the suction on the nozzle 2, thus increasing the relative proportion of hydrocarbon and producing a rich mixture. On the other hand, opening said valve will reduce the suction on 10 said jet nozzle and will increase the relative quantity of air, thus producing a "lean" mixture.

In like manner, if two or more of said passageways are open to the mixing chamber A', closing the valve 9, will increase the suction on all of said nozzles, increasing the proportion of hydrocarbon and by reducing the aggregate size of the air openings, correspondingly reducing the proportion of air, 20 thus producing a richer or leaner mixture as the valve 9 is closed or opened.

The air passageways 2', 3', 4', 5' and 6' and thus the nozzles 2, 3, 4, 5 and 6 are controlled by suitable valves, constructed and 25 arranged for opening and closing said air passages separately and in succession. As shown, said valves and the means for operating the same are as follows:—

Extending across the mixing chamber A' 30 and having bearings in the end walls thereof is an operating shaft 12 to which oscillatory movement is adapted to be imparted by means of a usual operating mechanism, not shown, which comprises a crank arm 13 secured to said shaft so as to rotate therewith and a connecting rod 14 pivoted to said crank arm. Pivoted on said shaft, preferably adjacent to opposite ends thereof, are what may be appropriately designated 35 40 shutter valves 15 and 16, the outer sides of which are concentric with said shaft 12 and are fitted to the curved lower side 17 of the mixing chamber which is also concentric with said shaft. Pivotal movement in opposite directions—that is toward and from each other—is adapted to be imparted to said shutter valves 15 and 16 by means of operative connection with the shaft 12. As 45 shown, said connection consists of slides 18 and 19, one located adjacent to each end of the mixing chamber. Formed in said slides are slots 20 and 21, through which, respectively, extend the shaft 12 and a rod 22, the ends of which are secured in the end walls 50 55 of the carburetor and which extends substantially parallel with said shaft 12. Endwise movement in opposite directions is adapted to be imparted to said slides 18 and 19 by means of crank arms 23 on the shaft 60 65 12 which are connected to lugs 24 on said slides by links 25 the opposite ends of which are pivotally connected to said crank arms and lugs. Secured in the slides 18 and 19 are pins 26 which engage downwardly divergent slots 27 and 28 formed in the end plates

or walls 29 and 30 of the shutter valves 15 and 16, which are extended so as to overlap each other. Thus, as said slides are raised and lowered, movement will be imparted to said shutter valves toward and from each other. By a proper divergence of the slots 70 27 and 28, it is obvious that said shutter valves may be opened and closed with desired rapidity.

The slides 18 and 19 are confined in operative position between the overlapping walls or plates 29 and 30 of said shutter valves and the hubs of the crank arms 23. 75

The air passageway 2' communicates with the mixing chamber at a point directly beneath the meeting edges of the shutter valves 15 and 16, when said valves are closed, thus, the initial movement of said shutter valves in opening will uncover said passageway 2' so that the suction of the motor will operate 80 to draw a mixture of hydrocarbon vapor and of air into the mixing chamber from said air passageway and the nozzle 2 located therein. As shown, also, the passageways 3', 4', 5' and 6' communicate with the mixing chamber 85 A' at points on opposite sides of said mixing chamber and about equal distances from the meeting edges of the shutter valves when closed, said passageways being arranged two on each side of said mixing chamber. To provide for opening and closing said air passageways 3', 4', 5' and 6' in succession as said shutter valves open and close, openings 32, 33 and 34 are formed in 90 said shutter valves each in line with one of said air passages, the relation being such that when said shutter valves are closed all of said air passageways will be closed or covered. As shown, said openings are arranged in line with the passageways 3', 4' and 5', respectively. Also, said openings are made of different operative lengths circumferentially of said shutter valves, their inner ends "cutting out" at the meeting edges 95 of said valves, the lengths of said openings being such that, at a desired interval of time before or after full opening of the passageway 2', preferably immediately after full opening thereof, the opening 32 will begin 100 to pass over the air passageway 3'; and, in like manner, the openings 33 and 34 and the edge of the shutter valve 15 will pass over 105 and uncover the air passageways 4', 5' and 6', respectively. 110

With the described construction, it is obvious 115 that the quantity of hydrocarbon feed to the engine may be regulated with great precision and nicety and also that the proportion of air and hydrocarbon may be accurately varied to produce an effective mixture. 120

To effect the object of the invention, as it relates to breaking up the hydrocarbon supplied to the motor and for thoroughly mixing 125 the hydrocarbon vapor and air, the dis- 130

charge opening 1 from the carbureter is controlled by a suitable valve which is operatively connected with the means for operating the shutter valves 15 and 16 so that 5 said valves will open and close together, the relation being such, however, that the shutter valves 15 and 16 will open more rapidly than the valve which controls said discharge opening 1. As shown, said discharge opening 10 1 is controlled by shutter valves 35 and 36 which are practically identical in construction with the shutter valves 15 and 16, excepting that they do not have the overlapping end plates or walls 29 and 30 of said 15 shutter valves 15 and 16, and which are pivoted to the rod 22 in substantially the same manner as said shutter valves 15 and 16 are pivoted to the shaft 12.

The means for opening and closing said 20 shutter valves 35 and 36 consists of links 37 and 38 the opposite ends of which are pivotally connected to the slides 18 and 19 and to the shutter valves 35 and 36, respectively, the points of pivotal attachment to said 25 slides being above their points of pivotal attachment to said valves, whereby downward movement of said slides will open and upward movement thereof will close said shutter valves.

30 With the described construction, it is obvious that, when the slides 18 and 19 are moved downward to separate the shutter valves 15 and 16 a sufficient distance to open or uncover the air passageway 2', the shutter valves 35 and 36 will also be opened but to a less extent, and that the opening of said shutter valves will continue as said slides are depressed to open the different air 35 passageways 3', 4', 5' and 6'. Due to the fact that the size of the discharge opening from the carbureter is graduated to correspond to the opening or uncovering of different numbers of air passageways, it is 40 obvious that the mixture in the chamber A' will pass through the discharge opening from the carbureter at a high velocity, which will cause the particles of hydrocarbon to strike the shutter valves 35 and 36, the impact operating to break up said particles 45 of hydrocarbon. Also, as the air and hydrocarbon vapors pass out of the carbureter, they will converge toward the contracted discharge opening, thereby effecting an intimate association and intermixing thereof, 50 which will produce a uniform explosive mixture of high efficiency.

55 Preferably, also, I supplement the breaking up and mixing action of the shutter valves 35 and 36 by baffle plates which extend across the mixing chamber A' between the air admission openings and the discharge opening and which are adapted to impart an eddying effect to the current of mixed air and hydrocarbon vapor, the impact of 60 the hydrocarbon particles against said baffle

plates operating to break up and finely subdivide the same and the eddying action produced thereby operating to effect a thorough mixing of the air and hydrocarbon vapor. As shown, said plates comprise a 70 central V-shaped plate 39 the sides of which diverge upwardly and upwardly inclined plates 40 arranged at each side thereof, the inclination of said plates being such that they will divert the current passing from 75 the air admission openings to the discharge opening and break it up into a number of conflicting currents, which will produce the eddying and mixing effect desired. Said baffle plates preferably extend crosswise of 80 the mixing chamber, that is substantially at right angles to the opening of the valves 35 and 36. My invention, however, contemplates the use of any desired or approved form of baffle plate arranged in any desired manner. 85

I claim:—

1. In a carbureter, the combination of a casing provided with a mixing chamber, a plurality of air admission passageways and with a discharge opening, nozzles in said air admission passageways which communicate with a source of hydrocarbon supply, and a valve for controlling said air admission passageways comprising sections which 95 are movable toward and from each other and which coöperate to open and close said air admission passageways and to expose the hydrocarbon nozzles positioned therein, respectively, in succession, whereby the 100 quantities of air and of hydrocarbon may be varied in pre-determined fixed proportions, substantially as described.

2. In a carbureter, the combination of a casing provided with a mixing chamber, a plurality of air admission passageways and with a discharge opening, nozzles in said air admission passageways which communicate with a source of hydrocarbon supply, and a valve for controlling said air admission passageways constructed and arranged for opening said passageways in succession beginning with a centrally located passageway and for closing them in reverse order, whereby the 105 quantities of air and of hydrocarbon may be 110 varied in pre-determined fixed proportions, substantially as described.

3. In a carbureter, the combination of a casing provided with a mixing chamber, a plurality of air admission passageways comprising a central passageway and passageways on both sides thereof, and said mixing chamber being also provided with a discharge opening, nozzles in said air admission passageways which communicate with a source of hydrocarbon supply, and a valve for controlling said air admission passageways comprising sections which are movable toward and from each other, constructed and arranged for opening and closing said 125 130

air admission passage-ways, the relation being such that the central passageway will be opened first and closed last, and alternate passageways on opposite sides of said central passageway will be opened and closed in succession, substantially as described.

4. In a carbureter, the combination of a casing provided with a mixing chamber, a plurality of air admission passageways and 10 with a discharge opening, nozzles in said air passageways which communicate with a source of hydrocarbon supply, a valve for controlling said air admission passageways comprising sections which are movable to- 15 ward and from each other, constructed and arranged for opening and closing said air admission passageways in succession, and a baffle which extends across the mixing chamber of said carbureter casing between the air 20 admission passageways and the discharge opening thereof, substantially as described.

5. In a carbureter, the combination of a casing provided with a mixing chamber, a plurality of air admission passageways and 25 with a discharge opening, nozzles in said air admission passageways which communicate with a source of hydrocarbon supply, valves which control said air admission passageways and said discharge opening, re- 30 spectively, each of said valves comprising sections which are movable toward and from each other and the valve which controls said air admission passageways being constructed and arranged for opening and closing said 35 passageways in succession, and a baffle which extends across the mixing chamber of said carbureter between the air admission passageways and the discharge opening, substantially as described.

40 6. In a carbureter, the combination of a casing provided with a mixing chamber, a plurality of air admission passageways and with a discharge opening, nozzles in said passageways which communicate with a 45 source of hydrocarbon supply, and a valve which controls said air admission passageways comprising sections which are movable toward and from each other, said valve sections being provided with openings of 50 different operative lengths which aline with said air passageways, respectively, substantially as described.

7. In a carbureter, the combination of a casing provided with a mixing chamber, 55 a plurality of air admission passageways and with a discharge opening, nozzles in said passageway which communicate with a source of hydrocarbon supply, a valve which controls said air passageways comprising 60 sections which are movable toward and from each other, said section being provided with openings of different operative lengths which aline with different air passageways, a valve operating shaft rotatably mounted 65 in said carbureter casing and operative con-

nexion between said shaft and said valve sections whereby oscillation of said shaft will impart movement to said valve sections toward and from each other, substantially as described.

8. In a carbureter, the combination of a casing provided with a mixing chamber, a plurality of air admission passageways and with a discharge opening, nozzles in said passageways which communicate with 70 a source of hydrocarbon supply, a pivoted shutter valve which controls said air passageways provided with openings of different operative lengths which aline with different air passageways, a valve operating shaft rotatably mounted in said carbureter casing and operative connection between said shaft and said shutter valve whereby oscillation of said shaft will impart pivotal movement to said valve in opposite directions, said connection comprising a slide, guides therefor, a crank arm on said valve-operating shaft, a link which connects said arm with said slide and connection between said slide and shutter valve, 80 substantially as described.

9. In a carbureter, the combination of a casing provided with a mixing chamber, a plurality of air admission passageways and with a discharge opening, nozzles in said 95 passageways which communicate with a source of hydrocarbon supply, a pivoted shutter valve which controls said air passageways provided with openings of different operative lengths which aline with different air passageways, a valve-operating shaft rotatably mounted in said carbureter casing and operative connection between said shaft and said shutter valve whereby oscillation of said shaft will impart pivotal movement to said valve in opposite directions, said connection comprising a slide, guides therefor, a crank arm on said valve-operating shaft, a link which connects said arm with said slide and a pin 100 in said slide which engages a cam slot in said shutter valve, substantially as described.

10. In a carbureter, the combination of a casing provided with a mixing chamber, a plurality of air admission passageways and with a discharge opening, nozzles in said 115 passageways which communicate with a source of hydrocarbon supply, a pair of pivoted shutter valves which control said air admission passageways and which are provided with openings of different operative lengths, a valve-operating shaft rotatably mounted in said valve casing and operative connection between said shaft and shutter valves whereby oscillation of said 120 shaft will impart pivotal movement to said shutter valves toward and from each other, substantially as described.

11. In a carbureter, the combination of a 130

- casing provided with a mixing chamber, a plurality of air admission passageways and with a discharge opening, nozzles in said passageways which communicate with a source 5 of hydrocarbon supply, a pair of pivoted shutter valves which control said air admission passageways and said discharge opening respectively, a valve-operating shaft rotatably mounted in said valve casing, a 10 crank arm thereon, a slide, a link which connects said crank arm with said slide whereby oscillation of said shaft will impart movement to said slide in opposite directions, and operative connection between 15 said slide and said pairs of shutter valves, respectively, adapted to impart pivotal movement thereto toward and from each other, said connections comprising links which connect the shutter valves controlling 20 the discharge opening with said slide, substantially as described.
12. In a carbureter, the combination of a casing provided with a mixing chamber, a plurality of air admission passageways and 25 with a discharge opening, nozzles in said passageways which communicate with a source of hydrocarbon supply, a pair of pivoted shutter valves which control said air admission passageways and said discharge opening respectively, a valve-operating shaft 30 rotatably mounted in said valve casing, a crank arm thereon, a slide, a link which connects said crank arm with said slide whereby oscillation of said shaft will 35 impart movement to said slide in opposite directions, and operative connection between said slide in opposite directions, and operative connection between said slide and said pairs of shutter valves, respectively, adapted to 40 impart pivotal movement thereto toward and from each other, said connections comprising a pin secured in said slide which engages cam slots formed in the shutter valves which control the air admission passageways, and links which connect said slide 45 with the shutter valves which control the discharge opening from said carbureter, substantially as described.

In testimony that I claim the foregoing as my invention, I affix my signature in the presence of two subscribing witnesses this 28th day of August, 1914.

JOHN J. KARTHEISER.
